Specification of Letters Patent.

Patented Oct. 31, 1916.

Application filed March 23, 1914. Serial No. 826,818.

To all whom it may concern:

Be it known that I, CLARENCE R. BUMBARGER, a citizen of the United States, residing at Kansas City, in the county of Jackson and State of Missouri, have invented certain new and useful Improvements in Fireproof Doors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to fire-proof doors, or the like, and more particularly to a metal door or window of that class, which, when in open position, is reeled within a housing at the top of door opening; the principal object of the present invention being to provide a fire-proof structure of this character, which will close automatically in case of fire.

It is also an object of the invention to provide mechanical means for carrying out the general purpose of the invention, and in accomplishing these objects I have provided the improved details of structure herein-after described and illustrated in the accompanying drawings, wherein:

Figure I is a perspective view of a fire-proof door containing my improvements and illustrating the door in partially closed condition; a part of the door casing being broken away to illustrate the arrangement of the door on its reel. Fig. II is an end view of the parts shown in Fig. I. Fig. III is an enlarged elevation of the reel, its casing and automatic controlling mechanism; the curtain being removed from the reel and the casing being in vertical section. Fig. IV is an end view of the door casing showing the automatic latch for holding the reel, in its operative position and holding the housing damper open, the cover being removed. Fig. V is a rear view of the latch mechanism. Fig. VI is a view of the same parts with the latch released. Fig. VII is an enlarged longitudinal section of the reel, showing the fixed and free sections that provide the automatic release. Fig. VIII is a perspective view of the reel and casing; the latter being in section. Fig. IX is an en-

larged cross section of the same. Fig. X is a horizontal section of part of the door frame with the guide. Fig. XI is a detail perspective of the upper portion of one of the door guides.

Referring more in detail to the parts: 1 designates the frame of any door or window, 60 but in order to simplify the following description I will refer to the same as a door only, although it is understood that the device is equally adapted for use in connection with a window.

Fixed to the frame 1 adjacent the door opening are vertical guides 2, each preferably comprising an angle-iron 3 having a flange 4 bolted, or otherwise secured to the frame at one end, and having a plurality of 70 slots 4' through which bolts 5' may be projected to fasten the guide to the wall and permit expansion thereof should the parts become overheated.

Secured to a flange 5 of the angle-iron 3 75 is the flange 6 of an angle-iron 7, the opposite flange 8 of which is directed inwardly relative to the frame, and fixed to the flange 6 of the iron 7 is the flange 9 of an iron 10, the flange 11 of which parallels the flange 8 80 of iron 7 and is spaced therefrom to provide a guide channel 12.

The upper end of the outer angle-iron flange 7 terminates at or adjacent the top of the door opening in an outwardly turned 85 lip 14 (Fig. IX), and the upper end of the inner flange 11 extends upwardly and rearwardly into contact with the door frame, and together with the outward lip 14 forms a hopper-like mouth 15 through which the 90 flexible curtain, hereinafter described, may travel; the flaring mouth obviating jamming of the curtain should the reel upon which the curtain is wound be turned rapidly and unwind the curtain faster than the 95 latter is lowered in its guides.

Mounted on the door frame, above the guides, is a casing 16 comprising end plates 17 having circular forward edges and flat rear edges, the latter provided with angle-irons 18, having flanges 19 bolted, or otherwise rigidly secured to the door frame, with the bolts 20 preferably extending through the guide flanges 19. The body of the casing 100 comprises a stiff sheet of metal 22, which 105 overlies the edges of the end plates 17 and

has its lower edge projected beneath the out-turned lips 14 of the guide flanges 8 and secured thereto, while its upper edge terminates flush with the door frame; both edges 5 being provided with beads 23 to form a rigid structure, and the ends of the sheet being secured at intervals to the plates by brackets 24. At one end of the casing is a chamber 16' formed by the extended edges 10 of the metal sheet 22, which contains the automatic mechanism hereinafter described, and which is provided with a removable cover 16" for entirely inclosing the parts.

Each of the end plates 17 has a bearing 27, 15 and revolvably mounted in said bearings are the tubular shaft members 28-28', each of which has its outer end projected through the bearing and plate and its inner end in abutment with the mating member. One of 20 the shaft members contains collars 29, and located within said collars and fixed thereto and to the shaft member is a coupling rod 31, the outer end of which projects from the end of its shaft member into the opposite 25 shaft member, where it is revolvably mounted in bushings 32 that are contained within collars 33, which are riveted, or otherwise rigidly secured to the shaft member 28, so that the shaft members 28-28' may revolve freely 30 cf but coaxially with each other.

Revolvably mounted on each of the shaft members, is a drum 34, preferably comprising a hub portion 35 that is spaced from the shaft by roller bearings 36, and having a peripheral flange 37. Surrounding the shaft is a band spring 38 the opposite ends of which are fixed to the drum flange 37 and to the shaft respectively; washers 40 being mounted on the shaft and positioned to retain the 40 roller bearings in the hub and to cover the open face of the drum. A cotter-pin, or the like 41, is fixed to the shaft adjacent the end of the hub to retain the drum against outward longitudinal movement along the shaft. 45 The drums on the separate shaft members are identical and each is preferably provided with peripheral sockets 43 in which the reel bars 44 are seated; the said bars being of such number and arrangement about the drums 50 that they form a rigid, skeleton reel upon which a flexible curtain 45 may be wound; the upper end of the curtain being fixed to the reel by a clamp bar 46, having bolts 47 extending therethrough and through the end 55 of the curtain into one of the reel bars to hold the upper end of the curtain evenly and securely to the reel.

The curtain 47 is preferably composed of corrugated steel and its lower end carries a 60 bottom board 49, the ends of which are adapted for travel in the guides 2 and the lower edge of which carries the hanger bars 50 that form a footing for the board. A hanger bar 51 is secured to the outer face of 65 the board above the footing and adapted for

engagement with the lower bead of the casing plate 22, so that when the curtain is coiled, the opening to the casing is closed to prevent foreign matter from entering the casing.

I also preferably mount a damper 53 within the casing to prevent drafts therethrough and thereby obviate damage to the reel in case of fire; the specific construction of the damper preferably comprising a rod 71 54, which is mounted on the plates 17 and extends across the case above the reel, and a metal plate 55, which is rigidly mounted on the rod 54 and hangs over the reel, so that it contacts and is supported by the flexible 80 curtain member when the latter is rolled on the reel; it being apparent that the damper will yield when the curtain is moved thereunder, and that it closes the interior of the casing to shut off the passage of air about 85 the reel.

It is apparent that with the present construction, comprising the two spring drums, both of which are of the construction heretofore described with reference to the single 90 drum that has been specifically mentioned, and with the flexible curtain secured to the reel, the springs may be tensioned to balance the curtain, the spring tensioning mechanism preferably comprising disks 57, one of which 95 is fixed to the end of each of the shaft members and provided with laterally directed peripheral lugs 58, having apertures 59 for receiving a bar whereby the disks and shaft members may be revolved to tension the drum 100 springs. With the present automatic construction the disk 57 on the shaft member 28' is adapted for coöperation with a locking pin 60 that is adapted for projection through a bracket 61 on the fixed casing plate 17 to 105 hold the shaft firmly against revolution under tension of the spring, so that the drum spring on the shaft member 28' may remain under tension irrespective of the action of the spring on the shaft member 28. 110

Fixed to the shaft member 28 is a disk 57 similar to the disk 57 on the shaft member 28', but provided, in addition to the lugs 58, with peripheral bosses 63, which are adapted for engagement by a pawl 64 that projects 115 laterally from a lug 65, which is pivotally mounted on an arm 66 that is, in turn, pivotally mounted on a stud 68 on the adjacent casing plate 17. The end of the arm 66 is weighted to carry the pawl away from the 120 reel disk when the arm is unrestrained, and the free end of said arm is provided with a roller 69, which is adapted for holding engagement by a tooth 70 (Fig. V) on a hanging arm 71 that is pivotally mounted on a 125 stud 72 carried by a bracket 73 on the casing plate 17, so that when the hanging arm is in functional position, the arm 66 is supported on the tooth 70 and the pawl 65 held in position for restraining travel of the reel. 130

The lower end of the hanging arm 71 projects through a slot 71' in the chamber 16' and carries a cable 75, which is connected with a bracket 76 that hangs from the opposite casing plate 17, and interposed in said cable is a fusible link 77; the cable and link structure being adapted for retaining the hanging arm in locking position, and the lug 70 being inclined, so that when the fusible link is melted, weight of the arm 66 will push the hanging arm out of the way to allow the pawl to drop from the reel and free the reel, so that the door may be lowered by its own weight.

15 I prefer to retain the damper 55 out of contact with the reel and curtain under normal conditions, in order to prevent its wiping the curtain when the latter is reeled or unreeled, and in accomplishing this object, I extend the damper rod 54 through the casing plate carrying the latch mechanism and attach a crank member 79 to the projecting end of the rod. Pivotedly connected with the crank member is a depending link 80, having a slot 81 at its lower end, through which a pin 82 is projected into the hanging arm 71; the parts being so arranged that when the latch is set to hold the reel shaft, the damper is held in elevated position, away from the reel, but when the latch is released by fusing of the link, the damper is positively pulled down by the weighted arm, to shut off draft through the casing.

35 In arranging a door of this construction, the combined tension of the reel springs is adapted for balancing the weight of the curtain in about the proportion of two-thirds of the weight on the constantly active spring 40 on the shaft member 28', and one-third of the weight on the drum on the shaft 28, so that in case the fusible link is melted, the shaft member 28 may revolve freely in its bearing, and the curtain be freed from the tension of the spring on that member, so 45 that it may lower automatically against the tension of the single spring, thereby providing for automatic closing of the door in case of fusing of the link.

50 It is apparent that, under normal conditions, with the curtain under influence of both of the reel springs, the curtain may be opened by lifting on the rail 51 and lowered by pulling downwardly thereon. It is also apparent that the same structure is adapted 55 for use as a shutter, and, as there is no necessity for closing the ordinary fire shutter, except in case of fire, no further means is required for their manipulation as the closure will lower automatically when the link is fused under influence of the high temperature incident to a fire within or adjacent the building equipped with my improved device.

60 In using the door, presuming the parts to be constructed and assembled as described,

when the curtain is first installed in the casing, the permanently tensioned shaft member is revolved to tension the reel drum to the desired degree, and locked by means of the disk and bracket latch. The automatically releasable drum is then revolved in the same manner to tension its spring, and when the spring is tensioned to the desired degree, the pawl mechanism is set to hold the shaft member. With the parts set in this manner, when the curtain is lowered, the reel is revolved and both springs tensioned progressively; it being apparent that as the curtain is unrolled from the reel, its weight increases, but is balanced by the increased tension on the reel springs, so that the balance is maintained for the different positions of the curtain. Should a fire occur in the building, or adjacent the door, while the door is open, heat coming to the fusible link will melt the link and release the hanging arm 71, so that weight of the arm 66 will push the hanging arm aside to allow the arm 66 to drop, and when the arm 66 drops, the pawl leaves its contact with the boss on the reel disk, so that the shaft 28 is free to turn in its mountings. As soon as the shaft 28 is released as described, the spring on that shaft becomes ineffective and as the single spring on the shaft 28' is insufficient to support the weight of the door, the door automatically unreels and closes the door opening; the tension of the active spring being sufficient, however, to retard the lowering of the door and thereby cushion its drop to prevent damage to the door or to the sill with which it contacts in its lowermost position. It is also apparent that, under ordinary conditions, the damper will be held out of contact with the reel or door, but that when the door operates automatically in case of fire, the damper is pulled down against the reel or door to shut off draft through the casing and obviate damage to the reel and door by fire that may be drawn into the casing.

It is apparent that this construction may be used as a door or shutter in the ordinary manner, but that it will automatically close in case of fire, and that when released for the automatic closure its descent is cushioned to prevent damage to the door or its mounting.

Having thus described my invention, what I claim as new therein, and desire to secure by Letters Patent, is:

1. The combination with independently rotatable tubular shaft sections arranged in longitudinal alignment, of a coupling rod fixed in one shaft section and rotatably mounted in the other shaft section, a drum rotatably mounted on each shaft section, springs connecting the drums with respective shaft sections, and means for connecting the drums to form a reel.

2. The combination with independently rotatable, tubular shaft sections, arranged in longitudinal alinement, of bearing collars fixed in the shaft sections, a coupling rod 5 fixed in the collars in one shaft section and rotatably mounted in the collars in the other section, a drum rotatably mounted on each shaft section, springs connecting the drums

with relative shaft sections, and means connecting the drums to form a reel.

In testimony whereof I affix my signature in presence of two witnesses.

CLARENCE R. BUMBARGER.
